CLAIM

The ornamental design for a grasshopper, as shown and described.

DESCRIPTION

FIG. 1 is a top axonometric view of a grasshopper showing the new design;

FIG. 2 is a bottom axonometric view of the grasshopper;

FIG. 3 is a left elevation view of the grasshopper;

FIG. 4 is a right elevation view of the grasshopper;

FIG. 5 is a top elevation view of the grasshopper;

FIG. 6 is a bottom elevation view of the grasshopper;

FIG. 7 is a front elevation view of the grasshopper;

FIG. 8 is a rear elevation view of the grasshopper;

FIG. 9 is a right elevation view of the grasshopper in an extended state; and,

FIG. 10 is a right elevation view of the grasshopper in a retracted state.
